UNITED STATES PATENT OFFICE.

THOMAS McWATTERS, OF WASHINGTON, DISTRICT OF COLUMBIA.

SHOE AND HAME FASTENER.

SPECIFICATION forming part of Letters Patent No. 235,271, dated December 7, 1880.

Application filed April 17, 1880. (Model.)

To all whom it may concern:

Be it known that I, THOMAS McWATTERS, a subject of the Queen of Great Britain, residing at Washington, in the District of Columbia, have invented certain new and useful Improvements in Shoe and Hame Fasteners; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Referring to the drawings, Figure 1 represents a perspective of my shoe or other fastener. Fig. 2 is a longitudinal sectional view of the same, showing it attached to the flaps or edges of the article. Fig. 3 is a plan view 20 of the sliding bar; and Fig. 4 is a plan view of the blank or base plate, showing the same opened out as cut from one piece of sheet metal.

25 My invention relates to shoe and other fasteners; and the novelty consists in the construction and arrangement of parts, as will be hereinafter more fully set forth, and particularly pointed out in the claims.

The letter A of the drawings represents the 30 blank or base plate; B, the cogged or toothed lever, and C the sliding bar.

In carrying out my invention I take a piece 35 of sheet metal and stamp it out as shown in Fig. 4 of the drawings. The base-plate A has flanges a and a', which are bent upward at the dotted lines, as shown, to form a casing for the cogs on the lever B, and prevent the same from being clogged with dirt, dust, or other substances. The flanges a have holes b, 40 which receive a pin, b', in the lever B, and serve as a bearing for the said lever to operate. The base-plate A has side and horizontal flanges, c and c', which are cut from the said base-plate, and also bent upward and inward 45 at the dotted lines, to form guides for the sliding bar, which, together with the cogs or teeth d on the lever B, prevent the said sliding bar from being entirely removed from the base-plate.

The letter D represents barbs at each end 50 of the base-plate A, to secure my device to the article to which it is to be applied. The bar C has holes d', which receive the cogs or teeth d, and operate back and forth by the up-and-down movement of the said lever B. The 55 said sliding bar C has pin e at or near its outer end, to receive the opposite edge of the article. The lever B has a hole or catch at or near its outer end, so that when the said lever is depressed it secures itself under the catch 60 f on the pin or stud e, and serves to prevent the article from slipping over the said pin or stud.

F represent cone-shaped pieces on the back or upper side of the lever B. 65

When my device is applied to shoes the cone-shaped pieces are intended to represent two rows of buttons.

Having thus fully described my invention, what I claim as new, and desire to secure by 70 Letters Patent of the United States, is—

1. In a shoe or other fastener, the lever B, provided with a catch or keeper, e', at or near one end, and journaled in bearings with cogs or teeth d, meshing in holes d' of the sliding 75 bar C, said sliding bar having a stud, e, with a catch, f, all constructed substantially as described, and for the purposes specified.

2. In a shoe or other fastening, the blank or base A, having flanges a and a', c and c', 80 and barbs D, in combination with the lever B, having catch e', teeth d, and sliding plate C, having holes d', and catch f, constructed and operated substantially as specified.

3. In a shoe or other fastener, the lever B, 85 provided with the opening or catch e' at one end and the cogs or teeth at the other end, said lever being pivoted in the flanges a of the plate or blank A, in combination with the plate or blank A and the sliding plate C, having the perforations d', and the stud or pin e, with notch f, substantially as specified.

In testimony whereof I affix my signature in presence of two witnesses.

THOMAS McWATTERS.
